RATE OF RISE-DIVE INDICATOR

John D. Morgan, South Orange, and Percy B. Levitt, Millburn, N. J., assignors to Cities Service Oil Company, New York, N. Y., a corporation of Pennsylvania

Application April 14, 1945, Serial No. 588,376

10 Claims. (Cl. 73—179)

1
This invention relates to navigational instruments for submarine vessels and the like, and is more particularly concerned with a device for indicating quickly and precisely the rate at which such a vessel is diving towards the bottom of the sea or is rising to its surface.

It is essential to the safe navigation of underseas craft that the extent of submergence shall be known at all times, and suitable instruments are provided for that purpose. These depth gages, which read in terms of feet of submergence, give no indication of an equally important navigational factor involving the element of time, that is to say, the rate at which the submarine is diving from the surface or is rising towards it. It is quite evident, for example, that the safety of a submarine which is cruising below the surface while observing a prospective target through its periscope will depend largely upon the ability of the crew to maintain the craft on an even keel at a depth of from say 30 to 40 feet. Under these circumstances the vessel still retains some degree of buoyancy so that it has a constant tendency to rise, which must be offset by the reaction of its control planes driving through the sea. Accordingly when it is noted that the vessel has started to rise prompt action must be taken to adjust the control planes, in order that the vessel may not break surface and become an easy victim for its intended prey, or, conversely, submerge to the point where it loses sight of its target.

Need for prompt action in offsetting a rise of the vessel is made particularly vital by reason of the slowness with which these heavy vessels respond to elevational control. More need hardly be said concerning the importance of this matter to the crew of a vessel which is cruising near the surface. It will be recognized, however, that prompt action may be equally vital in a vessel which is operating at fairly great depths. There have been cases, for example, in which the crew of a submarine cruising far below surface has failed to note the beginning of a rise at even a very slight rate, with the result that enough momentum was built up in the vessel to cause it to break surface against the application of the fullest degree of corrective action.

It will be evident from the foregoing that the problem is not only one of knowing that a change of elevation is occurring, and of knowing that promptly, but involves equally a determination of the rate at which the submarine is rising or diving as a basis for the application of just that degree of plane deflection which is needed to

offset the change. In this connection it will be appreciated that over-control of a submarine may be just as disastrous in its results as under-control, and that the middle course can be judged properly only upon the basis of accurate knowledge.

The principal object of the invention is to provide a navigational instrument for indicating the rate at which the submarine is rising to the surface or is diving toward the bottom in such precise terms as fractions of feet per second, and equally one which is adapted to give an indication of a change of elevation within a fraction of a second after the inception of that change, and before the vessel has risen or dived more than a few inches from the level at which its commander has chosen to cruise.

It is a further object of the invention to provide an instrument of this kind which is not dependent for its proper functioning upon the total head of water acting upon its pressure-sensitive members, and which therefore responds just as rapidly and gives an equally accurate indication of the rate of dive or rise near the surface of the sea as it does when the submarine is operating well below the surface and at levels approaching maximum safe depths.

Another object of the invention is to provide a rate of dive-rise indicator having a safety valve which serves to shut off communication with the open sea when the pressure upon its sensitive members approaches what may be considered a maximum safe value, and which accordingly serves to protect the instrument from damage when the vessel is forced to operate at extreme depths.

The foregoing and other objects of the invention as well as its various features will be more fully developed in the following description and one embodiment is illustrated in the accompanying drawings, in which

Fig. 1 is a plan view of a rate of rise-dive instrument showing its indicating pointer and scale;

Fig. 2 is a sectional view taken on the line 2—2 of Fig. 1;

Fig. 3 is a sectional view taken on the line 3—3 of Fig. 2; and

Fig. 4 is a sectional view of a fragment of the instrument, the section being taken on the line 4—4 of Fig. 2.

In the drawings, and referring to Figs. 1 and 2, numeral 9 indicates an instrument body having a dial 10 mounted in its front end, which dial is marked off in tenths of feet per second of rise

on one side of the zero point, and of dive on the other side; a pointer 11 mounted to rotate on a centrally located shaft 12 so that its tip may sweep over the index marks on the dial to give a ready reading of the rate of change; and a protecting glass 13 lying between gaskets 14 and held in place by a bezel 15. The operating mechanism of the instrument, as may best be seen in Fig. 2, includes a metal bellows 16 which with a plate 17 secured to its rear end forms a movable wall between chamber 18 that is normally open to the sea through conduit 19, on the one side, and a liquid filled system which is open to atmospheric pressure in sump 20, on the other side, together with a heavy spring 21, which supports the bellows and is so calibrated as to permit limited movement thereof in direct proportion to the hydrostatic pressure acting upon plate 17.

The sea water chamber referred to above is formed in the illustrated instrument by a housing 22, and a cover 23 to which the forward end of bellows 16 is secured, both of these parts being firmly fastened to a flange 24 formed on the rear end of body 9 by suitable stud bolts 25. The vent 26 allows for the escape of air during the filling of chamber 18 with sea water, and is normally closed by plug 27. Various other constructional details of the sea water chamber will be considered at a later point.

The liquid filled system referred to above includes a conduit 28 leading from the bellows and terminating in sump 20 below the normal level of liquid 30 therein, and an orifice 31 for limiting the rate at which liquid may be expelled from the bellows into the sump. In the illustrated device this orifice is formed by tube 28a, coupled at 33 to the lower end of conduit 28 proper, and having a length such as to provide a desired fixed resistance. The use of a tube for this purpose means that the orifice may be large enough in cross sectional area to permit viscous flow so that the response of the instrument may be on a linear scale. It has the further advantage of making for manufacturing economy in that special parts do not have to be formed and assembled, and of making for ease of calibration of the finished device in that the total resistance of the orifice may be varied by adjustment of the length of the tube employed. It will be readily apparent, however, that where non-linear response in the completed instrument is desired with expanded scale readings near the zero mark, a conventional orifice plate may be employed in place of tube 28a to restrict the flow of liquid between the bellows and sump.

The liquid filled system also includes a pressure gage, generally identified by the numeral 34, which has a pressure sensitive member connected to conduit 28 at a point between bellows 16 and fixed orifice 31, so as to respond to changes in pressure existing in the liquid filled system. In the preferred instrument a gage of the Bourdon type is employed, having its pressure sensitive tube 35 connected mechanically through shaft 36, a multiplying sector 37 and pinion 38 to shaft 12 on which the indicating pointer is carried.

It will be assumed as a basis for a discussion of operating principles, that the instrument illustrated in the drawings is mounted in a submarine with its chamber 18 completely filled with sea water and open to the sea through conduit 19. If the vessel is lying on the surface, the pressure acting upon the outside of bellows 16 will be substantially atmospheric pressure and will be balanced by atmospheric pressure acting upon liquid

30 in sump 20, through a vent which is shown at 39, spring 21 in this case being fully distended, and applying no force to plate 17. As soon as a dive is started, however, the forces acting upon the bellows will be unbalanced, and the building up of pressure in chamber 18, corresponding to the hydrostatic head of sea water acting upon the vessel, causes a displacement of the bellows to the left as viewed in Fig. 2, against the reaction of spring 21, as well as against the resistance to flow of liquid through orifice 31. The pressure in the liquid filled system accordingly rises to whatever valve is required to overcome the resistance of the orifice, and is of course reflected by an expansion of tube 35, and a consequent movement of pointer 11 across the face of dial 10.

It will be evident to those familiar with the art that the pressure which is attained in the liquid filled system bears a direct relationship to the force which is causing the liquid flow, and represents a measure of the rate at which the vessel is diving. If the dive is a rapid one, for example, pressure in chamber 18 continues to build up and continues to displace the bellows to the left at a maximum rate, against the reaction of spring 21 and the resistance to flow of liquid from the bellows through orifice 31. The pressure needed to maintain flow through conduit 28 will be correspondingly high, and the indicating pointer of the instrument will therefore be swept across the face of the dial to indicate that the dive is approaching a maximum of two feet per second. In the course of a less rapid dive, however, and a consequent less rapid building up of pressure in chamber 18, a lesser pressure will be required in the liquid filled system to maintain liquid flow through orifice 31, and the deflection of the indicating pointer will be correspondingly smaller.

So much for the operation of the instrument to indicate the rate at which the submarine is diving. Assuming now that the vessel levels off at some chosen depth, it will be apparent that the pressure in chamber 18 quickly reaches a static value. Under these circumstances, flow of liquid from the bellows rapidly drops off until such time as the pressure in chamber 18 acting upon plate 17, is exactly balanced by the force of spring 21. Concurrently, of course, the pressure in the liquid filled system falls off, allowing the pointer 11 to swing back towards its zero point. At the point at which equilibrium is reached there will, of course, be no flow in the liquid filled system, the pressure therein will be zero, and the tip of the pointer will stand opposite the zero mark on the dial to indicate that there is no tendency on the part of the vessel either to rise or to dive.

Further consideration of the operating principles of the instrument will be based upon an assumption that the submarine starts to rise from the level at which it has been cruising and which formed the basis of the foregoing discussion. Any movement of the vessel in an upward direction must necessarily be accompanied by a decrease in the hydrostatic head of sea water acting upon plate 17 in chamber 18. The balanced condition which was discussed above will therefore immediately be disturbed, with spring 21 in this case displacing the bellows to the right as viewed in Fig. 2. In the course of this displacement liquid 30 will necessarily flow from sump 20 through conduit 28 into the bellows, and again that flow will be resisted by orifice 31. The pressure in conduit 28 will accordingly drop below atmos-

pheric pressure, resulting in a collapsing of Bourdon tube 35, and a swinging of pointer 11 in a counterclockwise direction. In this case, as with the one previously discussed, the pressure which is built up across orifice 31 will be in direct proportion to the rate at which the pressure in chamber 18 is changing, and will accordingly constitute a measure of the rate at which the submarine is rising. If upward movement of the vessel is quite gradual, a correspondingly small pressure will suffice to maintain flow into the bellows, and the negative pressure existing in conduit 28 will be such as to produce a correspondingly small movement of pointer 11. Conversely, a rapid rise of the vessel, and a rapid falling off of pressure in the chamber 18, will result in the creation of a relatively large difference between atmospheric pressure acting on liquid 30 and tending to force it from sump 20, and the pressure existing in the fluid filled system at the Bourdon tube. In this latter case therefore, the pointer will show a high rate of rise, approaching perhaps the maximum of two feet per second which the instrument is designed to indicate.

The utility of an instrument of the foregoing kind is largely dependent upon its sensitivity to small changes in pressure affecting its collapsible bellows, and particularly to the speed with which it responds to those changes. The illustrated device meets both of these requirements with a high degree of satisfaction. Thus it is adapted to respond to a change in pressure in chamber 18 of from six to nine inches of water, which is to say that it responds to a similar change of position of a submarine, and of equal importance, it will reflect that change within about one-fifth of a second after its inception.

This remarkable sensitivity and quickness of response is attributable to several factors. First it will be noted that we employ a liquid in the collapsible bellows system rather than a gaseous medium. Since the liquid is itself substantially incompressible, any displacement of the bellows in either direction is accompanied, to all intents and purposes instantaneously, by a flow of liquid through orifice 31, and by an equally quick building up of a pressure difference across the orifice to initiate a deflection of the Bourdon tube. Secondly, we find that best results are obtained by maintaining the liquid at a substantially constant viscosity so that its resistance to flow through orifice 31 will also be constant. We prefer therefore to employ a liquid which has a minimum viscosity change over a wide range of temperature fluctuation. In this connection we have found that a solution of about 47.75 per cent by weight of tricresyl phosphate, about 42.0 per cent by weight of ethylene glycol monobenzyl ether, about 10.0 per cent by weight of triethylene glycol di-2-ethylbutyrate, and about .25 per cent by weight of rust inhibitor, is particularly well suited for use in the foregoing device. It will be appreciated, however, that other liquids may be found which will serve equally well, or that controlled heating may be employed as a means of maintaining the viscosity of whatever liquid is employed, at a substantially constant value.

The third factor which affects the sensitivity of the instrument, and a major one, has to do with the volumetric capacity of the pressure sensitive member 35. In this connection we prefer to employ a Bourdon type of gage because the tube of such a device requires a minimum change of volume to produce a maximum deflection of pointer 75

11. It is equally important, however, to maintain a proper ratio between the change in volume of element 35 required for maximum pointer deflection, and the displacement of bellows 16 which is needed to produce that maximum pointer deflection. We have found that eminently satisfactory results can be obtained by the use of a tube and bellows system in which this volumetric displacement ratio is about 1:10. In the illustrated device, for example, tube 35 requires a change of volume of about .00045 cubic inch to produce a deflection of pointer 11 from zero to the maximum of two feet per second, in either direction. The displacement of bellows 16 needed to build up a pressure across the orifice corresponding to the two foot mark on the dial involves a displacement of about .0046 cubic inch of liquid. The proportioning of the elements in this ratio of 1:10, or in a greater ratio, means that only an insignificant part of the liquid in the system has to be forced into tube 35 to cause its distention, and that the major part of the fluid is always available for flow through the orifice to build up an indicating pressure in the liquid filled system. It accordingly means that there is substantially no lag between the time at which an unbalanced condition is created on opposite sides of the plate 17, and the time at which that unbalance is indicated by the movement of pointer 11.

It will be apparent from the foregoing that the operation of the instrument is not dependent upon the actual pressure existing in the chamber 18, but rather upon the rate at which that pressure changes. It accordingly follows that the instrument responds equally as well to changes which occur when a submarine is operating near the surface of the sea as it does when operation is at great depths. This statement must be qualified, of course, to the extent that the pressure in chamber 18 must not be allowed to build up to a valve such as to burst the bellows 16, or to cause a permanent distortion of spring 21. The illustrated instrument was designed, for example, for operation at all depths up to 250 feet. In order to protect it against permanent damage in the event that it is carried to greater depths, we preferably provide a valve head 40, carried by bellows 16, which is adapted to be forced against a seat 41 when the pressure in chamber 18 reaches a value corresponding to about 250 feet of water. The closing of that valve accordingly cuts off communication between pressure chamber 18 and the sea whenever the instrument is being subjected to what might be termed the maximum safe value for its operation. Once the valve closes, of course, the instrument becomes inoperative, and stays so until the vessel rises above the 250 foot level. In this connection it should be noted that valve head 40 is but very little larger than the valve opening in the rear wall of housing 22 which seat 41 surrounds, and accordingly that the vessel need rise only a very little bit above the 250 foot level before that valve opens to reestablish communication with the sea, and to place the instrument again in operating condition.

The exact arrangement and location of the safety valve is not a matter of primary importance to the invention. In the illustrated instrument the valve head 40 is located in an extension 42 of housing 22 and is connected to the bellows system by having its stem 43 threaded into a central opening in plate 17. With this arrangement, the collapsing of the bellows 16 responsive to increasing pressure in chamber 18 forces the

head against seat 41 surrounding opening 44 in the rear wall of housing 22. It may also be noted that the valve is made accessible by the provision of a cap 45 which is threaded to the rear end of extension 42, and which carries a threaded connection for communicating line 19. Any other suitable valve arrangement which serves a similar function may also be adopted in building instruments in accordance with our invention.

In the foregoing discussion reference was made to the fact that the illustrated instrument has been designed for operation at a maximum depth of about 250 feet. It will be appreciated, however, that the invention is not so limited in its utility and that instruments which are capable of withstanding much greater heads may readily be built in accordance with the principles hereinbefore outlined. In such cases, of course, the valve 41 may be dispensed with if suitably strong springs and bellows are employed, or may be adjusted to shut off communication of the sea at a pressure corresponding to the safe maximum pressures to which these instruments may be subjected.

Having described our invention, what we claim is:

1. A rate of dive-rise indicator for submarine vessels comprising a diaphragm, means for applying pressure to one side of said diaphragm which is directly proportional to the hydrostatic pressure of the sea at varying depths; a spring for supporting said diaphragm, said spring being so calibrated as to permit displacement of said diaphragm in direct proportion to the pressure applied thereto; a liquid filled system including the other side of said diaphragm as a wall thereof and a sump which is open to atmospheric pressure; a flow restricting orifice in said system between said bellows and said sump; and a gauge for indicating pressure changes in said system resulting from displacement of said diaphragm, said gauge and said diaphragm having a displacement ratio of the order of 1:10.

2. A rate of dive-rise indicator for submarine vessels comprising a collapsible bellows; means for applying pressure to one side of said bellows which is directly proportional to the hydrostatic pressure of the sea at varying depths; a spring for supporting said bellows, said spring being so calibrated as to permit displacement of said bellows in proportion to the pressure applied thereto; a liquid filled system including the other side of said bellows as a wall thereof, and a sump which is open to atmospheric pressure; a flow restricting orifice in said system between said bellows and said sump; and a gauge for indicating pressure changes in said system, resulting from the displacement of said bellows.

3. A rate of dive-rise indicator according to claim 2 characterized by a shut-off valve for limiting the application of pressure to the first-mentioned side of said bellows, and means for actuating said shut-off valve responsive to the displacement of said bellows.

4. A rate of dive-rise indicator for submarine vessels comprising a collapsible bellows; means for applying a pressure to one side of said bellows which is directly proportional to the hydrostatic pressure of the sea at varying depths; a spring for supporting said bellows, said spring being so calibrated as to permit limited displacement of said bellows in proportion to the pressure applied thereto; a liquid filled system including the other side of said bellows as a wall thereof, and a sump which is open to atmospheric pressure; a flow

restricting orifice in said system between said bellows and said sump; and a gauge for indicating pressure changes in said system resulting from the displacement of said bellows, said gauge and bellows having a volumetric displacement ratio of the order of 1:10.

5. A rate of dive-rise indicator for submarine vessels comprising a pressure chamber; a collapsible bellows constituting one wall of said chamber; means for admitting sea water to said chamber to apply pressure to the outside of said bellows equal to hydrostatic sea pressure; a spring for supporting said bellows, said spring being calibrated to permit limited displacement of said bellows in proportion to the hydrostatic pressure applied thereto; a sump which is open to atmospheric pressure; a passageway connecting the inside of said bellows with said sump at a point below the normal liquid level therein; said bellows, passageway, and a portion of said sump being filled with liquid; a tube of restricted cross section for resisting liquid flow in said passageway between said bellows and said sump on a linear scale; and a pressure gauge connected to said passageway between said bellows and said orifice for indicating the rate of dive and rise of a submarine.

6. A rate of dive-rise indicator for submarine vessels comprising a pressure chamber; a collapsible bellows constituting one wall of said chamber; means for admitting sea water to said chamber to apply pressure to the outside of said bellows equal to hydrostatic sea pressure; a spring for supporting said bellows, said spring being calibrated to permit displacement of said bellows proportional to the pressure applied thereto; a sump which is open to atmospheric pressure; a passageway connecting the inside of said bellows with said sump, said passage including a tube of restricted cross section which terminates in said sump at a point below the normal liquid level therein, and which serves as a viscous flow restricting orifice; and a Bourdon gage connected to said passageway between said bellows and said tube for indicating the rate of dive and rise of a submarine vessel, the Bourdon tube of such gage and said bellows having a volumetric displacement ratio of not substantially less than 1:10.

7. A rate of dive-rise indicator for submarine vessels according to claim 6 in which the liquid in said system has a substantially uniform viscosity over a wide range of temperature change.

8. A rate of dive-rise indicator for submarine vessels according to claim 6 in which the liquid in said system comprises a solution of about 47.75% of tri cresyl phosphate, about 42% of ethylene glycol mono benzyl ether, about 10% of triethylene glycol di-2-ethyl butyrate, and about 0.25% of a rust inhibitor, said percentages being by weight.

9. A rate of dive-rise indicator for submarine vessels according to claim 6 characterized by a shut off valve for said means for admitting sea water, and means operative responsive to the building up of pressure in said chamber for closing said valve.

10. A rate of dive-rise indicator for submarine vessels according to claim 6 characterized by a shut-off valve for said means for admitting sea water, and means connecting said valve and said bellows whereby collapsing of the latter causes a closing of the valve.
